UNITED STATES PATENT OFFICE.

FRED A. DENNETT, OF SHEBOYGAN, WISCONSIN.

DESIGN FOR A BENT-WOOD CHAIR-SEAT.

SPECIFICATION forming part of Design No. 29,235, dated August 16, 1898.

Application filed July 18, 1898. Serial No. 686,295. Term of patent 14 years.

To all whom it may concern:

Be it known that I, FRED A. DENNETT, a citizen of the United States, residing at Sheboygan, in the county of Sheboygan and State of Wisconsin, have invented and produced a new and original Design for Bent-Wood Chair-Seats; and I do hereby declare the following to be a full, clear, and exact description of the same, reference being had to the accompanying drawings, forming a part thereof.

In the said drawings, Figure 1 is a plan view. Fig. 2 is a central longitudinal vertical section on the line 2 2 of Fig. 1. Fig. 3 is a transverse vertical section on the line 3 3 of Fig. 1; and Fig. 4 is a front elevation, looking from the line 4 4 of Fig. 1, of a bent-wood chair-seat embodying my new design.

My design relates to the new and original shape or configuration of the article.

The leading or essential feature consists in the unitary design for a bent-wood chair-seat made the subject of illustration, comprising the peculiar and novel shape of the top or upper portion A thereof, which along the rear end and along the sides of the top is of substantially the same horizontal plane or level. Just forward of the flat or level rear portion of the top a there is a depression on a semicircular line at the rear extending between the points b b, the shape of this depression at the longitudinal center being shown as extending from the point b' to about the point c', and thence at the said center the top A rises upwardly on the line of a shallow ogee to the extreme forward point d', as best shown in Fig. 2. The form of this depression transversely near the rear of the seat on the line 3 3 between the points c c is best shown in Fig. 3. The sides at the front of the top at 40 d d are of substantially the same elevation

and plane surface as at the rear a; but between the front central point d' and the side points d d on each side thereof the said front of the top A is formed on rounded concave lines, having their greatest points of depression at e e and thence rounding upwardly to the outer points d d and similarly rounding upwardly to the central front point d', all as best shown in Fig. 4. The front corners of said top A (best shown in Fig. 1) are formed on rounded convex lines between the points f g f g, the front line (shown at the left in Fig. 1) following the line of two ogees, united at the point h, between the point g and the central point d', on each side of the latter. The two front depressions (on each side of the front central elevation, which finds its highest point at d') extend backward and blend into the first-named semicircular rear depression.

Minor features of this design comprise inward-curved concave lines between the points i j in the side edges of the top A and a projection of the continuous ogee-shaped front of the said top A over the correspondingly-shaped front piece B of the supporting-frame of the seat.

Having thus described my invention, what I claim as new, and desire to secure by Letters Patent, is—

The design for a bent-wood chair-seat, as herein shown and described.

In testimony that I claim the foregoing I have hereunto set my hand, at Port Washington, in the county of Ozaukee and State of Wisconsin, in the presence of two witnesses.

FRED A. DENNETT.
